CIGAR PERFORATING DEVICE

David Elliott, Johnstown, Pa.

Application May 2, 1933, Serial No. 668,910

3 Claims. (Cl. 131—20)

This invention relates to improvements in cigar perforating devices.

One of the main objects of the invention resides in a cigar perforator which may be inconspicuously supported upon the belt of a wearer and readily accessible for use when desired for puncturing the mouth end of a cigar prior to the lighting of the same, to avoid the practice of biting or clipping the end which sometimes results in the breaking down of the mouth end and the loosening of the tobacco to the extent that tobacco bits enter the mouth during the smoking of the cigar.

Another object of the invention is to provide a cigar smoker's article which embodies a cup shaped member having a piercing element centrally arranged therein, which punctures the mouth end of a cigar when inserted into the cup shaped member, the article being supported upon the belt of a wearer with the open side of the member facing toward the body of the wearer and serving as a guard to prevent the piercing member from uncomfortably contacting with the wearer's body, the belt adapted to be twisted to face the open side of the cup shaped member outwardly when use of the article is desired.

A further object of the invention is the provision of a cigar perforator which is simple and inexpensive of construction, easy to apply and remove from a belt, and which is neat and ornamental as not to detract from the dressy appearance of the wearer.

With these and other objects in view, the invention resides in the certain novel construction, combination and arrangement of parts, the essential features of which are hereinafter fully described, are particularly pointed out in the appended claims, and are illustrated in the accompanying drawing, in which:

40 Figure 1 is a view of my cigar perforator in position upon the belt of a wearer, and showing the belt twisted to position the device for use.

Figure 2 is a perspective view of the cigar perforator in position upon a belt and looking from the inside thereof.

Figure 3 is a vertical longitudinal sectional view through the cigar perforator and supporting belt and showing a cigar about to be inserted for perforation.

50 Figure 4 is a perspective view of the cigar perforator per se looking at the front thereof.

Figure 5 is a perspective view of a modified form of my invention showing the fastening clasp in an open position.

55 Figure 6 is a vertical longitudinal sectional

view through the form of the invention shown in Figure 5, but illustrating the clasp in clamping position upon a belt.

Referring to the drawing by reference characters, and particularly to the form of my invention shown in Figures 1 to 4 inclusive, the numeral 10 designates a substantially U-shaped clip or clamp member which when in applied position is of substantially inverted U-shape. The member 10 is constructed of a single piece of resilient metal and includes a relatively wide leg 11 and a narrow leg 12. The free end of the leg 11 is bent inwardly as at 13 whereas the free end of the leg 12 is curved outwardly as at 14, the leg 12 being slightly shorter in length than the leg 11. The curving of these legs facilitates the insertion of the clip upon a support and the same coacts to grip or clamp the device upon the support.

Fitting against the leg 12 is the closed end of a cup shaped member 15, and passing through the leg and the end wall of the cup shaped member is a piercing element 16, the inner end of the element being reduced and flattened into a rivet head 17 for securing the cup shaped member to the leg 12. The outer peripheral edge of the cup shaped member is flared outwardly to provide an annular flange 18 and the pointed end 19 of the piercing element 16 terminates short of the plane of the edges of the flange 18. The piercing element is disposed centrally within the cup shaped member to provide an equal distance from the axis thereof to the side walls of the cup shaped member.

Although the perforating device may be supported upon other wearing apparel, I have illustrated the same as applied to a man's belt 20, and in applying the same the clip 10 is slipped down over the top edge of the belt with the leg 11 disposed on the outside thereof and the cup shaped member 15 extending inwardly against the body of the wearer. The device is preferably clamped adjacent the front of the belt as illustrated in Figure 1 to permit access thereto when desired. By twisting the belt in the manner shown in Figure 1, the open side of the member 15 may be exposed to enable the mouth end 21 of a cigar 22 to be inserted so that the piercing element 16 enters the mouth end 21 and provides a draft opening which will permit of the free drawing of the smoke through the cigar when lighted.

As above stated, the open side of the cup shaped member faces in the direction of the body of the wearer, but the outwardly flared portion 55

or flanges 18 formed thereon bear against the body of the wearer and serve to prevent contact of the pointed end of the piercing element 16. In other words, the cup shaped member serves as a guard for preventing contact of the piercing element with the wearer's body.

If desired, the outer face of the leg 11 may be provided with the wearer's initials or any other form of decoration may be provided thereon.

10 In Figures 5 and 6 of the drawing, a slightly modified form of the invention has been shown and includes a pair of jaw members 23 and 24, the upper end of the member 23 being provided with diametrically opposed ears 25 for receiving pintles 26 provided on the upper end of the jaw member 24 whereby the two members are pivotally connected together. A flat spring 27 is interposed between the top of the jaw 24 and the adjacent portion of the jaw member 23 which 15 serves to normally force the two jaw members into clamping engagement. However, when the member 24 is swung to a fully open position off center, it will remain in such position until again moved to a position where the spring acts to close 20 the same. Inwardly extending teeth 28 are provided on the lower end of the jaw member 24 for embedding in the belt 29 when the clasp is 25 in applied position.

In this form, the cup shaped member 30 is set 30 in an opening 31 in the jaw member 24 and is welded or otherwise fixedly secured therein. A piercing element 32 is secured to the closed end wall of the cup shaped member 30 and extends centrally thereof, but short of the peripheral 35 flanged portion 33 of the cup shaped member. The operation of the perforating device shown in this form is identical to that hereinbefore explained.

While I have shown and described what I deem to be the most desirable embodiment of my invention, I wish it to be understood that such changes as come within the scope of the appended claims may be resorted to if desired.

Having thus described the invention, what I claim as new and desire to secure by Letters Patent of the United States, is:—

1. A cigar perforating device comprising a substantially U-shaped clip member, a cup shaped member fitting against one of the legs of said U-shaped clip member, and a piercing element secured to said leg and extending through the closed end wall of said cup-shaped member into the inside thereof.

2. A cigar perforating device comprising a substantially U-shaped resilient clip member, a piercing element extending outwardly from one of the legs of said clip member, and a guard member supported by said clip member and surrounding said piercing element and projecting beyond the plane of the free end thereof.

3. A cigar perforating device for smokers adapted to be worn upon the belt of a wearer comprising a U-shaped belt attaching member, a cup shaped guard member carried by one of the sides of said U-shaped attaching member, and a piercing element extending centrally from the closed end wall of said guard member and terminating inwardly of the plane of the peripheral edge of the side walls of said guard member, whereby the device may be worn upon the belt of a wearer with the open side of said guard member facing inwardly against the body of the wearer.

DAVID ELLIOTT.
